HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,297,758.

Specification of Letters Patent. Patented Mar. 18, 1919.

Application filed November 10, 1917. Serial No. 201,280.

To all whom it may concern:

Be it known that I, HENRY G. VOIGHT, a citizen of the United States, residing in New Britain, county of Hartford, and State 5 of Connecticut, have invented certain new and useful Improvements in Locks, of which the following is a full, clear, and exact description.

This invention relates to locks, and more 10 particularly to extensible cylinder locks which are adjustable for application to doors of different thickness.

The primary object of the invention is the production of an extensible lock which 15 permits a maximum range of adjustment with comparatively few parts, the parts being so constructed that a material increase is obtained in the length of the bearings for the guide pins and adjustable screw over the 20 type of extensible locks now in general use, without decreasing the range of adjustment.

Another object of the invention is to simplify and improve the mechanism by which 25 the extension is adjustably secured to the main part of the lock.

To these and other ends, the invention consists in the novel features and combinations of parts to be hereinafter described and claimed.

30 In the accompanying drawing:

Figure 1 is a side elevation of a cylinder lock embodying my improvement, showing the lock partly extended;

Fig. 2 is a similar view from the opposite 35 side of the lock;

Fig. 3 is an elevation of the lock shown in Fig. 1, looking in the direction of the arrow, the lock being shown in its shortest adjustment and the extension being shown 40 as cut by a section taken substantially on the line 3—3 of Fig. 5;

Fig. 4 is a rear end view of the main part of the lock, the extension with its guide pins and adjusting screw being removed;

45 Fig. 5 is a view showing the inner face of the extension with the pins and adjusting screw secured thereto.

My improved cylinder lock comprises a main part or cylinder lock proper 10, and an 50 extension 11 detachably connected therewith. The main part 10 is, for the most part, of usual construction, having a case 12, a face plate or escutcheon 13, a pin tumbler extension 14, and the usual key-plug or barrel 55 (not shown) inside of the case 12, which

barrel is locked against rotation by the usual pin tumblers (not shown).

In the embodiment illustrated, the lock proper 10 is provided with a plurality of lugs 15, 16 and 17 rigidly formed upon the 60 inner end of the main part of the lock. These lugs are provided with cylindrical ends or bosses positioned to project beyond the end of the main part of the lock. The lug 15 is provided with a threaded drill hole 65 18 and the lugs 16 and 17 are provided with smooth drill holes 19 and 20. The key barrel, which is not shown, is provided with the well-known washer 21 having a key slot formed therein. The washer may be secured 70 to its barrel by means of screws 22. The projecting cylindrical ends of the lugs 16 and 17 are partially cut away in order to provide a clearance space in which the washer 21 rotates.

75 The detachable extension 11 for the cylinder lock may consist of a disk-like head 23 provided with the usual threads upon its periphery, by which the cylinder may be secured to the case of the mortise lock. 80 However, it will be apparent that my invention is not necessarily limited to this particular type of head. The extension head 23 is provided with a plurality of smooth guide pins 24 and 25, which are rigidly mounted 85 in the head and project therefrom at right angles to the face of the same. The head 23 is further provided with an adjusting screw 26. This screw is rotatably mounted in the head and is held against longitudinal 90 movement in one direction relatively to the head by the tapered head of the screw being seated in a correspondingly tapered countersunk opening in the extension head, and the screw is held against longitudinal movement 95 in the opposite direction by a washer 27, which washer is secured in place on the screw by setting up a portion of the screw around the washer. The head of the screw is provided with the usual screw-slot, by 100 means of which it may be rotated.

The head 23 is provided also with the well-known roll-back 28, which roll-back may be conveniently operated by means of a pair of pins 29, 30, rigidly secured to the 105 roll-back. The roll-back is held against longitudinal movement relatively to the head by a washer 31 rigidly secured thereto and mounted inside of the head 23. The washer 21, which is mounted on the key barrel, (not 110

shown) is provided with drill holes 32 and 33. These holes extend almost entirely through the key barrel and operatively receive the projecting pins 29, 30.

5 From the construction already described, it will be apparent that the extension 11 is detachably mounted upon the main part of the lock by the smooth guide pins 24, 25, and that the extension may be adjusted to 10 any desired position relative to the main part of the lock by the adjusting screw 26. The roll-back 28 will be operatively connected to the key-operated barrel in any adjustment of the extension by the projecting pins 15 29, 30 which are slidably received in the openings 32, 33, and in the key barrel.

The disk-like head 23 is provided with sockets or clearance spaces 34, 35 and 36 formed concentric with the pins 24, 25 and screw 26 respectively. The sockets are formed in the head 23 to receive the projecting cylindrical ends of the lugs 15, 16 and 17. This structure permits the head to be moved toward the inner end of the main 25 part of the lock until it abuts against the same. It should be noted that it is the cylindrical portion of each lug and not the lug proper that extends beyond the inner face of the main part of the lock; that is, the shoulder formed where the cylindrical portion of each lug joins onto the lug proper, is flush with the end of the main part of the lock. This structure provides an abutting face upon each lug proper lying in the plane of 30 the inner end of the lock, against which the disk 23 will seat firmly when the lock is given its shortest adjustment.

The disk-like structure of the head 23 forms a housing in which the lugs 15, 16 and 40 17 project; when the parts assume the position shown in Fig. 3, the arrangement being such that when the lock is given its shortest adjustment, the head will not abut against the ends of the lugs but the inner face of the head will contact with the inner face of the lock.

By constructing my lock so that the lugs are permitted to project within the head of the extension, I am able to materially increase the length of the bearings for the pins 24, 25, and the bearing of the adjusting screw 26, without decreasing the range through which the extension 11 may be adjusted. Furthermore, this arrangement by 50 which the ends of the lugs may project into the head 23 enables me to obtain a range through which the extension may be adjusted greater than the entire length of the main part of the lock, it being apparent that as the length of the lugs is increased beyond the end of the main part of the lock, the range of adjustment is correspondingly increased providing the lugs are permitted to project into the extension. In other words, by extending the lugs beyond the end of the main

part of the lock, I form what may be termed a telescopic adjustment between the sliding pins and the lugs, thereby increasing the range of adjustment in proportion to the extent the lugs are permitted to project into 70 the extension.

In order to form a clearance space for the ends of the pins 24, 25 and adjusting screw 26 when the extension assumes its shortest adjustment, the escutcheon 13 is provided 75 upon its inner face with recesses or sockets 37, into which the ends of the pins just mentioned may extend.

It will be apparent from the above description of my extensible lock that I have 80 devised a simple, serviceable lock which permits of a long range of adjustment for the extension and which at all times provides a strong, firm supporting connection between the main part of the lock and its extension. 85

The disk-like head 23 is preferably formed of solid metal turned or cast into the shape of the desired disk and then drilled or bored to form the sockets or clearance spaces 34, 35 and 36. 90

Without limiting myself to the construction shown, I claim:

1. An extensible cylinder lock comprising a main part and an extension adjustably connected thereto, said main part having an 95 integral lug for supporting said extension, said lug having a cylindrical end projecting beyond the end of said main part of the lock into a socket of the extension.

2. An extensible cylinder lock comprising a main part and an extension adjustably connected thereto, supporting means rigidly secured to said extension, and lugs 100 co-operating with said supporting means formed integral with the main part of the lock, said lugs having cylindrical ends projecting beyond the end of said main part, and said extension having receiving sockets formed therein for said projecting ends. 105

3. An extensible cylinder lock comprising 110 a main part and an extension adjustably connected thereto, an adjusting screw for said extension, and a co-operating lug for said screw formed integral upon the main part of the lock, said lug having a cylindrical end projecting beyond the end of the main part of the lock, and said extension having a socket formed therein for receiving said projecting end of the lug. 115

4. An extensible cylinder lock having a 120 main part and an extension, and a plurality of means upon the extension for adjustably supporting said extension upon the main part of the lock, said extension having a clearance socket formed therein adjacent each supporting means. 125

5. An extensible cylinder lock comprising a main part and an extension, said extension comprising a solid cylindrical head having projections extending therefrom to 130

support the head upon the main part of the lock, said head also having a clearance socket formed therein adjacent each projection.

- 5 6. An extensible cylinder lock comprising a main part and an extension adjustably connected thereto, and lugs integral with said main part for supporting said extension, said lugs having cylindrical ends projecting beyond the end of the main part of the lock and forming abutments upon said lugs, positioned to contact with the inner face of the extension, whereby the extension may be firmly seated upon said abutments.
- 10 15. 7. An extensible cylinder lock comprising a main part and an extension adjustably connected thereto, guide pins rigidly secured to said extension, and pin-receiving lugs integral with the main part of the lock, said lugs having reduced ends projecting beyond the end of said main part, and said extension having receiving sockets formed therein for said projecting ends.
- 20 8. An extensible cylinder lock comprising

a main part and an extension adjustably connected thereto, and lugs integral with said main part for supporting said extension, said lugs having cylindrical bosses projecting therefrom beyond the end of the main part of said lock, thus forming shoulders adjacent the cylindrical bosses, said shoulders being positioned to be engaged by the inner face of the extension, whereby the extension may be firmly seated upon said shoulders.

30 9. An extensible cylinder lock comprising a main part and an extension, supporting pins secured to said extension, pin receiving lugs upon said main part, said lugs being positioned to extend beyond the end of the main part of said lock, and said extension having lug receiving sockets formed therein, whereby the range through which said extension may be adjusted is increased.

35 40 45 In witness whereof, I have hereunto set my hand on the 7th day of November, 1917.

HENRY G. VOIGHT.
